[57] **CLAIM**

The ornamental design for a hinge guard for a glide swing, as shown and described.

DESCRIPTION

FIG. 1 is a perspective view of a hinge guard for a glide swing showing my new design;

FIG. 2 is a side elevational view thereof with the opposite side being a mirror image thereof;

FIG. 3 is a front elevational view thereof with the rear being a mirror image thereof;

FIG. 4 is a top plan view thereof; and,

FIG. 5 is a bottom plan view thereof.

The broken line showing of a portion of a swing is for illustrative purposes only and forms no part of the claimed design.

FIG. 1

FIG. 2

FIG. 3

FIG. 4

FIG. 5
